COMPARTMENT DOOR LATCH

Charles Ledin, Stamford, Conn., assignor to The
Yale & Towne Manufacturing Company, Stam-
ford, Conn., a corporation of Connecticut

Application March 29, 1944, Serial No. 528,561

3 Claims. (Cl. 292—227)

1

This invention relates to a latch and more particularly to a latch to be used on an automobile compartment door.

Latches of the general type must provide extreme ease of operation and it is one of the objects of my invention to contribute a latch that may be very easily operated, preferably by the depression of a push button. It is a further object of this invention to provide a latch of the class described in which the manually operated part, preferably a push button, may be readily assembled relatively to the latch after the application of the latch to the compartment door. This makes it possible to provide any one of a series of different push buttons, as for instance push buttons of different colors, to match the particular color combination of the automobile.

A further object of the invention is the provision of a latch that may be readily assembled to the compartment door without the utilization of screws or conventional fastening devices.

A still further feature of the invention resides in the utilization of a novel operator for the latch, on which is to be mounted the latch bolt proper, so that movement of the operator will contribute movement of the latch bolt. As a feature of this portion of my invention, I provide a unique mounting for a spring between the latch bolt and the operator for simultaneously projecting the latch bolt into latching position and for projecting the operator into its normal position for manual actuation.

I have thus set forth briefly the objects of my invention and the features thereof in order that those skilled in the art may better appreciate the relation between my invention and the numerous prior art structures. Naturally, the contribution of my invention may readily be embodied in other mechanical forms, so that my invention should not be limited to the specific structure herein-after set forth.

In describing my invention I shall refer to the drawings, of which Fig. 1 is a vertical section through my latch showing it applied to a compartment door. Fig. 2 is a view similar to Fig. 1 but illustrating the latch bolt in its retracted position. Fig. 3 is a section taken along lines 3—3 of Fig. 1. Fig. 4 is a view looking from the right towards Fig. 3 and showing better the means for maintaining my latch assembled to the compartment door.

Referring now more particularly to the drawings, reference numeral 10 indicates a compartment door positioned in closed relation to a compartment, the upper surface of which is

2

designated by reference numeral 11. A strike 12 is secured by a rivet 13 to the surface 11 and is adapted for cooperation with a latch bolt 14 forming part of the latch assembly L of my invention.

My latch assembly L includes a mounting member designated by reference numeral 15 applied to door 10, and having a bore 16 within which slides what I term an operator 17. The latch bolt of my invention is pivoted through the short shaft 18 to the operator 17, and this short shaft 18 rides in opposed slots 19 formed in the mounting member 15 for guiding the operator 17. A further bore 20 is formed in the mounting member 15 and leads to the bore 16. Within the bore 20 there is mounted a push button 21 that may be formed of some plastic decorative material with the color thereof matching the color of the car if that is desired. A surface 22 within the bore 20 limits the inward movement of the push button 21 from the position of Fig. 1 to the position of Fig. 2.

A spring 23, rather complex in form, is held as shown in assembled relation to the operator 17, and is adapted to enter a V groove 24 of the push button 21 to resist outward movement of the push button 21 from the bore 20. The formation of the spring 23 is such that with the operator 17 in its position of Fig. 1, the push button 21 may be readily inserted into assembled relation to the operator by a flexing of the spring 23 as will be readily understood. Thereafter the push button 21 will remain in assembled relation to the latch assembly, although it may be removed at any time by a forceful pull thereon to overcome spring 23.

A spring 25 bears at one end against the spring 23 and the operator 17. At its other end spring 25 is mounted about a lug 26 on the latch bolt 14 and presses the latch bolt into its position of Fig. 1. It simultaneously presses the operator 17 into its position of Fig. 1 and against the shoulder 27 between the bores 16 and 20. The latch bolt 14 is held against further pivotal movement in a clockwise direction from the position of Fig. 1 by a cam surface 28 formed on the latch mounting member 15. It is of course now obvious that when the parts are in the position of Fig. 1 the latch bolt 14 effectively cooperates with the strike 12 to prevent opening movement of the door 10. With the parts in this position, should the push button 21 be moved from the position of Fig. 1 to the position of Fig. 2, the cam surface 28 will effect the retraction of the latch bolt 14 against the pressure of spring 25 as the latch bolt moves

with the operator 17. It will be appreciated that the movement of the operator 17 will also be opposed by the spring 25.

In Fig. 2 the latch bolt 14 is shown depressed from coaction with the strike 12 so that the door 10 may readily be opened. Release of the push button 21 thereafter, will allow the spring 25 to project the latch bolt 14 and to move the operator 17 to its normal position of Fig. 1. The push button 21 will of course also be moved to its position of Fig. 1. I believe that the very simple construction of my invention, the extreme minimum of parts, its ease of operation and the ready assembly of the latch mechanism will now be apparent.

Referring now more particularly to Figs. 3 and 4, it will be noted that at each side of the mounting member 15 there is provided a pin 30 about which is coiled a wound torsion spring 31. One leg 32 of each spring 31 lies in a groove 33 at each side of the mounting member 15. The other leg 34 of each spring 31 lies against a metal reinforcing member 35 that forms part of the door 10. It will now be readily understood that in order to insert the latch mounting member 15 into the opening 36 formed in the door 10 and plate 35, the legs 34 of springs 31 are flexed out of the way, and the mounting member 15 is then moved to the position of Fig. 3. Release of the spring legs 34 will then cause them to spring into their position of Fig. 3, in which position they tend to move the latch mounting member 15 inwardly of the door and with the surface 37 of the mounting member firmly against the door limiting its inward movement. The springs 31, rather effectively prevent disassembly of the latch mounting member 15 from the door 10 and maintain the parts in operating position. The simple form of mounting thus contributed by me is extremely effective since it eliminates the need for standard fastening means such as screws and rivets, while simultaneously preventing all rattling and loosening of the parts.

I believe that the nature of the contribution of my invention will now be understood by those skilled in the art.

I now claim:

1. In a latch of the class described, a mounting member having a bore, an operator moving inwardly in said bore from a forward to an inward position, a latch bolt pivoted on said operator, a spring positioned between said latch bolt and operator so as to press the latch bolt in one direction into a limit position against the mounting member while pressing said operator in another direction into its forward position, said mounting

member camming said latch bolt into a retracted position against said spring when said operator is moved inwardly against said spring.

2. In a latch of the class described, a mounting member, an operator movable endwise in an opening in said mounting member, a latch bolt pivotally mounted on said operator for endwise movement therewith and for pivotal movement relatively thereto, a portion of said latch bolt extending into coaction with a strike, means whereby the inward movement of said latch bolt with said operator effects pivotal movement of said latch bolt relatively to said operator out of coaction with said strike, and a spring compressed between said latch bolt and operator for urging said latch bolt toward said strike and said operator outwardly of said mounting member.

3. In a latch of the class described, a mounting member, an operator movable endwise in an opening in said mounting member, a latch bolt pivotally mounted on said operator for endwise movement therewith and for pivotal movement relatively thereto, a portion of said latch bolt extending into coaction with a strike, means whereby the inward movement of said latch bolt with said operator effects pivotal movement of said latch bolt relatively to said operator out of coaction with said strike, a spring compressed between said latch bolt and operator for urging said latch bolt toward said strike and said operator outwardly of said mounting member, a push button movable endwise in said opening to move said operator inwardly, a holding spring for securing said push button to said operator, and said first spring maintaining said holding spring in securing position.

CHARLES LEEDIN.
